TOBACCO PIPE

Edward H. McArdle, Elizabeth, N. J.

Application April 21, 1933, Serial No. 667,138

4 Claims. (Cl. 131—12)

My invention relates generally to tobacco pipes and is more specifically directed to a smoke cooling and moisture removing unit adapted to be interposed between the pipe bowl and a bit or mouth piece in the smoke passage of the pipe.

The primary purpose of a unit of this kind, many forms of which are known to the art, is to cool the smoke and remove objectionable constituents therefrom so that the smoke is cool, relatively dry and sweet when it reaches the smoker's mouth.

Certain of the prior constructions have achieved these desiderata to a limited extent, but so far as I am aware none has been wholly satisfactory, and the principal object of my invention is to provide a unit of this general character by means of which a maximum of coolness, dryness and sweetness of the smoke drawn into the smoker's mouth is obtained.

I accomplish this object by a construction of the unit such that two distinct temperature zones or areas are created about the unit, the zone near the pipe bowl being the hot zone and that near the bit being the cool zone. The preferred structure includes a front cup or tube of relatively substantial capacity in which considerable turbulence of the smoke may occur, a connecting or intermediate rod of very small cross sectional area as compared with the cross sectional area of the cup or tube, and a rear adapter which is also preferably of general tubular construction but of less capacity than the front cup or tube.

The invention is illustratively exemplified in the accompanying drawing in which Fig. 1 is an elevational view, partly in section, of a smoking pipe with the unit positioned therein; Fig. 2 is a fragmentary sectional view through the pipe and unit; Fig. 3 is a longitudinal sectional view of a modified form of unit; Fig. 4 is a similar view of a still further modified form of unit; and Fig. 5 is a cross section on the line 5—5 of Fig. 2.

The unit of my invention is usable in most forms of tobacco pipe, that shown in the drawing comprising a bowl 10, a bowl stem or shank 11 communicating by a short duct 12 with the bowl, and a bit 13 having a tenon 14 engaging an undercut seat 15 at the rear of the bowl stem. The bowl stem also has the usual bore or chamber 16 of substantial internal diameter.

Structurally, my improved unit is desirably an integral body and comprises a cup or tube 17 having an open end in close proximity to the outlet end of the duct 12, a solid shank or connecting rod 18 extending lengthwise within the chamber 16, and an adapter 19 having a tubular extension

20 projecting into a countersunk seat 21 in the smoke passage 13^a of the bit. The rear wall of the cup 17 is provided with an outlet orifice 22 and the adapter 19 and its extension 20 are provided with the passages 23 and 24 at a suitable angle to each other.

Proper dimensioning of the several parts of the improved unit is an important factor in obtaining best results, although I desire to make it clear that my invention is not restricted to any absolute or relative dimensions of parts. It has been found in practice that if the average cross sectional area of the shank 18 throughout its entire length is less than one ninth the cross sectional area of the chamber 16 in which the unit is mainly lodged so little heat will be transferred from the cup 17 to the adapter 19 that the rear end, i. e., the end near the smoker's mouth, of the pipe is maintained cool throughout the smoking of the average pipeful of tobacco.

The cup 17 is desirably in the form of a cylinder whose wall is at least two millimeters in length along the shank bore 16 of the pipe and which is fairly closely fitted into the pipe shank. The cup is well hollowed out to present a large surface and the orifice 22 is relatively small to allow for the passage of smoke. Under these conditions, excellent turbulence of tobacco smoke flow through the cup 17 is obtained with resulting excellent heat transfer and excellent cooling or shock chilling in the immediate environs of the cup; therefore considerable moisture condensation takes place in the immediate forward end temperature zone, even when the cup is used in conjunction with a thin connector rod as described above. In other words, while preventing excessive moisture condensation on the thin connector rod 18, and also while keeping the rear or adapter end of the unit cool by the creation of two separate temperature zones, a well hollowed out cylindrical forward end will still condense out ample bitter tasting moisture to provide a cool sweet and enjoyable smoke, and perform this condensation at a point the farthest possible distance away from the mouth.

The smoke is "shock chilled" and most of the moisture is condensed just after leaving the pipe bowl 10, which is as it should be.

As intimated above, the ideal average cross sectional area of the rod 18 is one which will be as small as possible to prevent appreciable heat transfer through the rod from the forward end of the cup 17 and at the same time large enough to provide ease and safety in fabrication and use. The above noted area, viz., less than one

ninth that of the shank bore corresponds with a ratio of diameters of baffle to average of rod, of more than three to one.

The wall length of the cup 17 should exceed two millimeters in order to effectively prevent minute tobacco flakes from slipping by in case too much clearance of the cup from the shank bore occurs. The length should be less than that of the rod 18 to allow for a long thin slight heat conducting rod in the space allowed for installation of the unit. The length of the cup 17 need not exceed eight to ten millimeters in the average size pipe, provided enough of the cup is hollowed out to make the metallic surface presented to the smoke oncoming from the pipe bowl at least double that of the cross sectional area of the shank bore. This is ample to provide for a highly turbulent smoke flow through the hollowed out cylinder and therefore for the thorough smoke cooling and moisture condensation in the immediate vicinity of the cup.

Figure 3 discloses a modified form of unit in which the entire structure is somewhat heavier than that shown in Fig. 2. The cup 17^a is somewhat elongated and relatively thick walled, the rod 18^a is properly proportioned to the size of the cup and the adapter with its passages 23^a and 24^a is likewise proportioned to the other elements of the unit. The cup 17 is provided with the smoke outlet orifice 22^a.

The modification of Fig. 4 discloses a thin walled cup 17^b shorter than either the cup 17 or 17^a, a connecting rod 18^b and adapter 19^b having the passages 23^b and 24^b.

In smoking a pipe containing a unit such as that described above, the hot smoke issuing from the bowl 10 and reaching the cup 17 has relatively great turbulence imparted to it, thus causing very pronounced cooling and the condensation of moisture as well as precipitation of solids or semi-solids. The smoke, thus pre-cooled and sweetened, flows through the orifice 22 into and through the chamber 16 to the relatively offset passages 23 and 24 where additional cooling and purification are effected. When the smoke reaches the smoker's mouth through the bit 13 it is cool and sweet, free of all or substantially all its objectionable constituents.

I claim:

1. In a tobacco pipe comprising a bowl, a chambered bowl stem and a passaged bit with a duct providing communication between the bowl and stem, the combination therewith of a smoke cooling and moisture removing unit comprising a tubular member of materially greater internal diameter than the diameter of said duct and having one end open and its opposite end provided with an outlet orifice of smaller area than the open end, an intermediate connecting rod extending lengthwise within the chamber in the bowl stem and an adapter in proximity to the bit. 80

2. In a tobacco pipe comprising a bowl, a chambered bowl stem and a passaged bit, the combination therewith of a smoke cooling and moisture removing unit comprising an elongated cup member having an open end adjacent the pipe bowl and a restricted smoke outlet orifice in the wall constituting its opposite end, an intermediate connecting rod whose average cross-sectional area throughout its length is less than one ninth the cross-sectional area of the chamber in the bowl stem, and an adapter in proximity to the bit. 85

90

3. A smoke cooling and moisture removing unit for tobacco pipes comprising as an integral structure a cup having one end completely open and having a restricted orifice in the wall constituting the opposite end, a thin intermediate solid connecting rod and an adapter having an angular passage therethrough, the cup being at one end of said rod and the adapter at the other end thereof. 100

105

4. In a tobacco pipe comprising a bowl, a chambered bowl stem and a passaged bit, the combination therewith of a smoke cooling unit comprising a cylindrical cup having a wall length not less than 2 millimeters and having one end completely open in close proximity to the bowl and the wall on the other end provided with a restricted orifice, 110 an intermediate solid rod having an average cross sectional area throughout its length of less than one ninth the cross sectional area of the chamber in the bowl stem and an adapter having a tubular projection with passages at an angle to each other 115 through the adapter and through the tubular projection. 120
